UNITED STATES PATENT OFFICE.

FRANK SCHMIT, OF DOUGLAS, ARIZONA TERRITORY, ASSIGNOR OF ONE-HALF TO EDWARD A. TOVREA, OF BISBEE, ARIZONA TERRITORY.

BUTCHERING-TOOL.

No. 881,828.

Specification of Letters Patent. Patented March 10, 1908.

Application filed May 26, 1906. Serial No. 318,963.

To all whom it may concern:

Be it known that I, FRANK SCHMIT, a native-born citizen of the United States, residing at Douglas, in the county of Cochise 5 and Territory of Arizona, have invented new and useful Improvements in Butchering-Tools, of which the following is a specification.

This invention relates to butchering tools, being designed for performing the cutting 10 and sawing operations involved in butchering meat, and has for its objects to provide a comparatively simple, inexpensive device of this character which may be readily manipulated, one wherein the cutting and sawing 15 blades are driven by a common mechanism, and one in which either of said blades may be brought into play at will.

With these and other objects in view, the invention comprises the novel features of 20 construction and combination of parts more fully hereinafter described.

In the accompanying drawings: Figure 1 is a side elevation of a tool embodying the invention. Fig. 2 is a top plan view of the 25 same. Fig. 3 is a horizontal section taken longitudinally through the tool on the line 3—3 of Fig. 1.

Referring to the drawings, 1 designates a metal casing preferably of the form shown 30 having a removable side or face plate 2 and provided with bearings 3, in which are journaled a pair of relatively spaced driven shafts 4 extended transversely through the casing, through the rear side wall of which there is 35 entered a flexible drive shaft 5 terminally journaled in a suitable bearing 6 disposed at a point centrally between the shafts 4, there being fixed on the shaft 5 a gear 7 in mesh with pinions 8 fixed on the shafts 4, whereby 40 the latter are connected to be driven from the shaft 5.

Fixed upon one of the shafts 4 and for rotation therewith is a circular saw blade 9 having a toothed or serrated cutting edge 10, 45 there being fixed upon the other shaft 4 a circular cutting blade 11 having a sharpened cutting edge 12, it being noted in this connection that the casing is of a form to house the upper portions of the blades 9 and 11, the 50 lower portions of which are projected below the casing and present exposed active portions of an extent equaling about one-half the surface area of the blades.

In practice, during rotation of the shaft 5 which is driven from any suitable source of power motion will be transmitted through the gearing 7 and 8 to the shafts 4 for rotating the blades 9 and 11, either of which may be brought into action at will. It will be understood that the meat will be cut by means 60 of the blade 11 and the saw blade 9 be brought into play for cutting the bones, the tool being manipulated for this purpose by grasping the upper closed edge of the casing at its center and turning the tool endwise to 65 bring first one and then the other of the blades into contact with the material being operated upon.

It is to be observed that the tool, which is in a measure forcible, is adapted for free 70 manipulation by hand and may owing to the peculiar formation of the casing, which is wholly closed except at its lower edge, be without risk to the operator grasped for free manipulation.

Having thus described my invention, what I claim is:

1. In a tool of the type described, a casing open at one edge and having its upper portion formed to serve as a grip, a flexible 80 power shaft extended into the casing, a gear fixed on said shaft and located within the casing, a pair of driven shafts journaled in the casing, pinions within the casing and fixed on said shafts and in mesh with the 85 gear, and a pair of cutting blades fixed respectively on and for rotation with the driven shafts, said cutting blades being projected beyond the open end of the casing and the latter being wholly closed except at the point 90 of projection of the blades.

2. In a tool of the class described, the combination of a rotary knife, a rotary saw arranged in close proximity to the knife and overlapping the same, a gearing for simultaneously rotating the saw and knife, and a casing covering the gearing and saw and knife, said casing serving as a grip for working the tool.

In testimony whereof, I affix my signature 100 in presence of two witnesses.

FRANK SCHMIT.
